(57) **CLAIM**

The ornamental design for a circular food container, as shown and described.

DESCRIPTION

FIG. 1 is a perspective view of a circular food container showing my new design;

FIG. 2 is a front elevation view thereof, and the rear elevation, left side, and right side views being mirror images thereof;

FIG. 3 is a top plan view thereof;

FIG. 4 is a bottom plan view thereof;

FIG. 5 is a cross sectional view thereof, taken along the line 5-5 of FIG. 3, shown in an enlarged scale; and,

FIG. 6 is a cross sectional view of FIG. 5 thereof, shown in an enlarged scale, in environmental use.

The broken line portions show unclaimed subject matter only and form no part of the claimed design.
